NAIL DRIVER

Lars Frostad, Syracuse, N.Y., assignor, by mesne assignments, to Rockwell Manufacturing Company, Pittsburgh, Pa., a corporation of Pennsylvania
Filed Oct. 16, 1961, Ser. No. 145,056
2 Claims. (Cl. 1—46)

This invention relates to nail drivers of the conventional type provided with a magazine containing a supply of nails which are advanced to a delivery slot and driven downwardly through the slot into a work piece by a driver blade actuated by a blow from a hammer, or mallet. A nail device of this type is disclosed in the copending application of Heiko T. de Man, Serial Number 8,396, filed February 12, 1960, now Patent No. 3,022,509, dated February 27, 1962.

This invention has as an object a hammer actuated nailer embodying a novel arrangement permitting multiple blows in driving a nail but preventing the movement of a nail into the delivery slot until the previous nail has been driven all the way home, or completely set in the work piece.

The invention consists in the novel features and in the combinations and constructions hereinafter set forth and claimed.

In describing this invention, reference is had to the accompanying drawings in which like characters designate corresponding parts in all the views.

In the drawings:

FIGURE 1 is a vertical sectional view of the forward portion of a nailer embodying my invention.

FIGURE 2 is a view of the lower right portion of FIGURE 1, with a nail positioned in the delivery slot ready to be driven.

FIGURE 3 is a view, similar to FIGURE 2, showing the nail driven to near set position.

FIGURE 4 is a view, similar to FIGURES 2 and 3, showing the nail driven completely set and the next nail in the magazine displaced for movement through the nail passage into the delivery slot upon return upward movement of the nail driver.

FIGURE 5 is an isometric perspective view of the inner portion of the nose piece showing the nail passage and nail delivery slot.

FIGURE 6 is a perspective view of the lower portion of the nail driver.

FIGURE 7 is an enlarged vertical sectional view of the nose piece and nail driver with the nail driven near completion.

FIGURE 8 is a view taken on line 8—8, FIGURE 7.

FIGURE 9 is an isometric view of a modified form of nose piece.

FIGURE 10 is a vertical sectional view of the nose piece and forward end portion of the magazine incorporating a retaining spring for the displaced nail.

FIGURE 11 is a view taken on line 11—11, FIGURE 10.

FIGURE 12 is a view taken on line 12—12, FIGURE 10.

The nailer consists generally of an elongated body containing a nail magazine having a guideway for supporting a row of nails. The nails are advanced along the guideway toward the front end thereof by a spring actuated pusher. A nose piece is affixed to the forward end of the guideway and is formed with a nail delivery slot extending normal to the nail guideway, and the nose piece is formed with a passage to provide communication between the guideway and the nail delivery slot and through which the nails are advanced to the slot. When the driver is in the full up position, the lower end of the driver

2

is positioned below the upper ends of the nails in the plane of the guideway, whereby the nails cannot advance through the passage into the nail delivery slot. When a nail has been moved or displaced downwardly in the passage from the plane of the guideway, the head of the nail is then positioned below the lower end of the driver blade when the driver blade is in the up position. This permits advancement of the displaced nail into the nail delivery slot, so that upon the next downward movement of the driver blade, the nail can be driven home. However, if the blow from the hammer, or mallet, does not drive the nail completely home, and the blade is returned to up position by the plunger spring, the next nail then positioned in the passage, cannot advance into the delivery slot. This arrangement avoids the necessity of incorporating in the nailer a complicated structure, such as pawls and the like, to prevent return upward movement of the nail driver blade until the nail has been completely set. Such full stroke mechanisms conventionally used are not only costly to incorporate in the nailer, but require frequent maintenance.

The body of the nailer is of conventional form consisting of a pair of similar mating castings 10 secured together by screws 11. These castings are formed on their confronting sides with mating concavities to form a compartment for the magazine and at their upwardly extending front portions 12, they are formed to provide a recess in which a plunger 13 is mounted for sliding movement. The plunger is hollow and moves in telescoping relation over a stem 14 on which is positioned a helical compression spring 15 to yieldingly urge the plunger upwardly. The plunger is formed with a lengthwise extending slot 16 to receive the inner end of a pin 17 mounted in the body castings and serving to limit the upward movement of the plunger. A nail driving blade 18 is affixed to and depends from the plunger. The upper end of the plunger is provided with a knob 19 to receive a blow from a hammer, or mallet, to move the plunger 13 and blade 18 downwardly to drive a nail in a work piece.

A nose piece 20 is fixed to the forward end of the body and may be of one-piece construction or, as in the arrangement shown, it carries a plate structure 21 which may be of laminated arrangement, as shown in FIGURE 5, or of one-piece construction as shown in FIGURE 9. The plate 21 is formed on its inner side with a passage 23 confronting the forward end of the body and arranged in registration with the nail magazine guideway. This guideway may be in the form of a pair of bars 56 having their confronting edges rounded, see FIGURE 8, for engaging notches formed in opposite sides of the nails 24 in proximity to the head portion 25 thereof. With this arrangement, the nails 24 are supported in a row by the bars 56 and are advanced along the bars by a pusher 67 moved forwardly by a compression spring 80, more or less in the conventional manner, and as shown more particularly in the de Man application referred to.

The nose piece or plate assembly 21 thereof is formed with a nail delivery slot 30 in which the driver blade 18 is movable. This slot and the driver blade 18 are dimensioned to permit free downward movement of a nail being driven into the workpiece 33 which is shown in the form of a piece of wood flooring. These machines are used extensively for laying such flooring. In like manner, the passage 23 is dimensioned to permit the free movement of the nails being used from the guideway into the slot 30.

When the driver blade 18 is in the full up position, as shown in FIGURES 1, 2 and 3, the lower end portion of the blade is positioned below the plane of the guideway bars 56, that is, below the upper ends of the nails in the guideway whereby, as shown in FIGURE 1, the foremost nail in the row is prevented from moving out of the passage 23 into the delivery slot 30.

There is affixed to the rear or inner side of the driver blade 18, a nail engaging projection 41. This projection 41 is spaced upwardly from the lower end of the blade a distance such that when the blade has been moved to full down position to set the nail, as shown in FIGURE 4, the projection 41 has engaged the head of the nail in the passage 23 and has moved it downwardly below the plane of the nail guideway a sufficient distance so when the blade is returned to full up position by the spring 15, the lower end of the blade is positioned above the downwardly displaced nail, permitting it to move into the delivery slot 30, as shown in FIGURE 2.

The nails 24 are adhered together by an adhesive, and the foremost nail in the row, positioned in the passage 23, is sheared, or separated, from the next adjacent nail by the projection 41 upon full downward movement of the driver blade. The pusher 67, by the action of spring 89, maintains a pressure against the downwardly displaced nail sufficient to normally restrain descent of the nail further than is necessary to clear the lower end of the driving blade 18 when the same is in full-up position. Also, by this pressure and the adhesively coated abutting surfaces of the nails, normally upward movement of the displaced nail upon upward return movement of the driving blade is prevented.

Downward movement of the displaced nail may be readily avoided by simply providing a positioning shoulder in the passage 23 as, for example, ledges 43, or a bottom wall 44. In the case of the ledges 43, the shoulder is provided by forming the upper portion 45 of the passage 23 wider than the lower portion of the passage so as to accommodate the heads of the nails when headed nails are used, as nails 24 shown. If straight or headless nails are used, such as sash pins, the point end of the nail may rest on the bottom wall 44.

Any upward movement of the displaced nail upon return upward movement of the driving blade may be prevented by the retaining spring arrangement disclosed in FIGURES 10, 11 and 12. In this arrangement, the leg portions 47 of a U-shaped spring are positioned in the upper wider portion 45 of the passage 23. The upper ends of the leg portions 47 of the spring are connected by a cross portion 48 which is displaced inwardly and is positioned in a slot formed in the body castings 10, see FIGURE 10. The lower ends 49 of the spring legs 47 converge inwardly, see FIGURE 11.

The leg portions 47 of the spring are spaced apart a distance to permit movement of a nail 24 into the passage 23. Due to the inward displacement of the connecting portion 48 of the spring, the projection 41 on the driving blade can move downwardly between the spring legs 47 to displace the nail from the plane of the magazine guideway for engagement with the ledges 43. During this downward displacement of the nails, the ends 49 of the spring spread outwardly and return to normal position shown in FIGURE 11, with the lower edges of the portions 49 positioned above the head of the displaced nail 50. Accordingly, upward movement of the driving blade 18 cannot effect upward movement of the displaced nail 50.

The addition of the displacement projection 41 to the nail driver blade 18 results only in a negligible increase in the cost of the manufacture of the nailer, but yet the arrangement described provides a positive blockage of the movement of the nail into the delivery slot until the previous nail has been completely driven in the workpiece, regardless of the number of blows on the plunger in the driving of a nail. This arrangement thus prevents any possibility of the machine jamming because of improper feeding of the nails from the magazine to the delivery slot.

What I claim is:

1. A nail driver comprising a body formed with a nail magazine having an elongated guideway for supporting a row of nails, a nail pusher for moving said row of nails toward the forward end of said magazine, a nose piece affixed to the forward end of said magazine and being formed with a nail delivery slot extending normal to the plane of said guideway, said nose piece being also formed with a passage arranged in registration with said guideway intermediate said guideway and said slot, and serving for the passage of nails from said guideway to said slot by said pusher, a nail driver blade slidably mounted in said slot and being movable downwardly through the slot to full down position to drive a nail home in a work piece, means limiting the upward movement of said blade in up position with the lower end of said blade positioned below the plane of said guideway to restrain movement of the forwardmost nail in said row from said passage into the said slot, said blade having a nail head engaging portion spaced upwardly from the lower end of said blade a distance for engaging a nail in said passage in the plane of said guideway and, upon movement of said blade to full down position, to displace such engaged nail downwardly from the plane of said guideway to position the head of said nail below the lower end of said blade when the same is in up position, whereby the next succeeding nail in said row of nails in the guideway will move said displaced nail through said passage into said slot, by action of said pusher against the row of nails.
2. A nail driver comprising a body formed with a nail magazine having an elongated guideway for supporting a row of nails, a nail pusher for moving said row of nails toward the forward end of said magazine, a nose piece affixed to the forward end of said magazine and being formed with a nail delivery slot extending normal to the plane of said guideway, said nose piece being also formed with a passage intermediate said guideway and said slot, said passage being arranged in registration with said guideway and serving for the passage of nails from said guideway to said slot by said pusher, a nail driver blade slidably mounted in said slot and being movable downwardly through the slot to full down position to drive a nail home in a work piece, means limiting the upward movement of said blade in up position with the lower end of said blade positioned below the plane of said guideway to restrain movement of the forwardmost nail in said row from said passage into the said slot, said blade having a nail head engaging portion spaced upwardly from the lower end of said blade a distance for engaging a nail in said passage in the plane of said guideway and, upon movement of said blade to full down position, to displace such engaged nail downwardly from the plane of said guideway to position the head of said nail below the lower end of said blade when the same is in up position, and means in said passage for restraining vertical movement of said displaced nail, whereby the next succeeding nail in said row of nails in the guideway will move said displaced nail through said passage into said slot, by action of said pusher against the row of nails.
